UNITED STATES PATENT OFFICE

FREDERICK H. PETERSON, OF WATERTOWN, CONNECTICUT, ASSIGNOR TO THE PATENT
BUTTON COMPANY, OF WATERBURY, CONNECTICUT, A CORPORATION OF CONNECT-
ICUT

BUTTON ATTACHING MACHINE

Application filed April 8, 1931. Serial No. 528,680.

My invention relates to new and useful improvements in button attaching machines, and more particularly to the jaws and jaw operating mechanism that retain the tack or button fastener in position while the plunger forces a button head down onto the fastener, so that the fastener, in turn, will pierce the material to which the button is to be attached and jam up within the button head to complete the assembly.

The present application in its broadest aspects is similar to the type of button attaching machine shown in Patent, No. 1,567,882, granted to Franklin R. White, on December 29, 1925.

In that patent, the jaws and their mechanism are similar to the construction shown in the patent granted to Franklin R. White on June 17, 1924, and numbered 1,497,819.

In the form of jaw mechanism shown in that construction, it was necessary to have a certain bridge, which was attached to the jaw holding sleeve which, with the finger attached to the elbow, raised the attached button out of the jaws, so the operator was enabled to run through (that is, to attach one button after another without stopping the machine). With this new device, both the bridge and lifting finger are done away with and removes every chance of the operator catching the garment and misplacing buttons, causing delay.

The present invention has to do, therefore, with a new form of jaw mechanism and a different arrangement of certain parts of the machine, whereby the jaws are spread open as the button is attached, these jaws remaining open until the plunger has returned for substantially one-third of its initial upward stroke to thus provide plenty of time for the operator to move the cloth with the attached button from directly over the jaws and from beneath the plunger.

Still another object of the invention is to provide a novel type of jaw mechanism wherein not only will the jaws remain open while the plunger is making one-third of its upward stroke so that the operator will have plenty of time to move the cloth, but furthermore, should the operator fail at this

time to move the cloth, the jaws, when closing, will force the cloth with its attached button slightly upwardly, so that as the jaws again spring together they will not or cannot possibly grasp the head of the fastener that has just been forced into the cloth and up through the button head.

Still another object of the invention is to provide a button attaching machine wherein the jaws that encircle the tack or fastener will tightly hold the same during a part of the downstroke of the main plunger. Also, as the button head is forced from its receiver down onto the jaws, the jaws are sprung open by the button head and are automatically, by a mechanism to be described, forced down into a lower plane and out of the way, where they remain until the plunger has passed through one-third of its return upward movement. This gives the operator plenty of time to reposition the cloth for the reception of a new button. Again, should the operator fail to remove the cloth, there is no danger of the jaws, when rising to their normal plane, to again grasp the tack of the already attached button, but on the other hand they will force the cloth and attached button upwardly and beyond the gripping jaws.

Still another object of the invention is to provide a jaw mechanism that is synchronized with the movement of the plunger, so that after the plunger has descended substantially one-fourth of its stroke, a cam action will come into effect to put a downward pressure on the tack or fastener gripping jaws, that is, on the carrier of the tack gripping jaws. When the button is finally forced down on the fastener, the carrier of the jaws, now under a heavy spring pressure, will, with its jaws, be quickly forced to a lower plane and out of the way.

Furthermore, the jaws will remain in this lowered position until the plunger has passed through considerable of its upturned stroke, thus giving the operator plenty of time to remove the cloth with the attached button.

Still another object of the invention is to so construct the jaws and their mechanism

65

that the fastener will be firmly held in the jaws until a button is brought down on the same. During this period, the jaws remain locked within grooves in an anvil. As the button head is then forced onto the tack, the jaws are sprung outwardly and thus unlocked. At the same time, spring pressure is brought to bear on the carrier of the jaws, which is now greater than the pressure which normally holds the jaw carrier and jaws in their upper position. This greater pressure causes the jaws and their carrier, when the jaws are unlocked, to snap down entirely away from the tack, all of which will be more fully described as the specification proceeds.

With these and other objects in view, the invention consists in certain new and novel arrangements and combination of parts, as will be hereinafter more fully described and pointed out in the claims.

Referring now to the drawings showing a preferred embodiment.

Fig. 1 is a side elevation of the improved button attaching machine showing the plunger in its uppermost or normal position and showing the tack or fastener holding jaws in their closed or normal position;

Fig. 2 is a substantially vertical central section with parts removed for the sake of clearness, other parts being shown in elevation, the plunger being shown in its lowermost position, the tack or fastener holding jaws having sprung open, and the cam mechanism for lowering the jaws being shown in its operated position;

Fig. 3 is substantially a horizontal central section of the machine with parts removed, showing the tack jaws in their closed position with a tack held therein, and showing the cam and its mechanism for lowering the jaws in a normal position;

Fig. 4 is a similar view but showing the cam mechanism for forcing the jaw carrier downwardly in its moved position and the tack holding jaws being shown in their opened and lowered positions;

Fig. 5 is a detail bottom plan view of the cam, the cam being formed on what I term the tucker lever or plate;

Fig. 6 is an enlarged detail sectional view, partly in elevation, showing a portion of the plunger, button receiving jaws, tack receiving jaws, a movable sleeve or carrier which supports the jaws; the carrier and jaws being shown in their normal positions;

Fig. 7 is a similar view showing the plunger at the end of its downward stroke forcing the tack through the button head, the carrier being in its lower position and the jaws sprung to their opened and lowered positions;

Fig. 8 is a detail fragmentary sectional view showing the plunger on its return stroke, the jaws forcing the cloth and the

button head free from the jaws while the jaws are about to snap into position;

Fig. 9 is a similar fragmentary view showing the jaws as having snapped into position and showing how the same will clear the head of the tack of the button;

Fig. 10 is an enlarged detail view of the carrier for holding the button operating jaws and also showing the cam and the jaw carrier operating lever, the latter being shown in its normal position;

Fig. 11 is an enlarged detail side sectional view of the anvil and jaw carrier, the jaws being removed for the sake of clearness and showing the carrier in its upper and normal position;

Fig. 12 is a similar view with the jaw carrier in its lowered position;

Fig. 13 is a fragmentary front face view of the jaw carrier with the jaws removed;

Fig. 14 is a perspective view of the jaw carrier with the jaws removed;

Fig. 15 is a top plan view of the jaw carrier and anvil in place;

Fig. 16 is a bottom plan view of the lever for operating the jaw carrier.

Before referring specifically to the several views, it will be understood that only that much of the mechanism of the button attaching machine is shown as thought necessary to illustrate and describe the invention and to show how the tack jaws are operated and synchronized with the stroke of the plunger. The details for the movement and synchronization of the tucker slide and lock, the ratchet mechanism for the hoppers containing the buttons and button fasteners, and many other details of the machine shown in Patent, No. 1,567,882 are not mentioned or only inferentially mentioned or briefly described.

Referring now more particularly to the several views and to Fig. 1 for the moment, there is shown a metal base or table 1, from which extends the curved upright arm 2 integral with the base and slotted, as at 3, the slot extending from near the base to the upper end of the arm, where it is, in turn, made to form a bearing 4, in which there is a bushing 5 and in which operates the die or plunger 6. This plunger is slotted at its upper end, as at 7, to receive the connecting link 8, while the other end of the link is secured to the outer end of the main oscillating lever 10, the latter being fulcrumed, as at 11, in the upright arm 2, as may be seen in Figs. 1 and 2.

The lower end of the oscillating lever 10 has the bearing 12 for the reception of a connecting rod 14 (Fig. 1). Said lever may be oscillated in the manner shown in a previous patent granted to Franklin R. White on December 2, 1913 and numbered 1,079,968.

As may also be seen in Fig. 1, there is a magazine or hopper 15 for holding and sup-

plying the tacks or button fasteners which are fed down a chute (not shown) to a tucker slide 40 (see Fig. 3), where they are forced, one by one, onto a small head or block 16 which is the upper part of an anvil post 17, where the tack or button fastener gripping jaws hold the same while the button head is being forced thereon. It is these tack holding jaws, a carrier for the same, the anvil post just mentioned, and a cam mechanism for operating the jaw carrier and its jaws that form the gist of the present invention, all of which parts will be described in full as the specification proceeds.

The tucker mechanism just above referred to is shown and described in detail in the patent granted to Franklin R. White on December 29, 1925 and numbered 1,567,882. 20 As far as the specification has proceeded, the device is similar to the patent just above referred to, to wit, 1,567,882, with the exception of the arrangement of the jaws 18 and the anvil post 17.

25 Going back for the moment to the other general parts of the machine so that the synchronization of the plunger 6 with the action of the jaws may be understood, there is shown a hopper or magazine 96 for holding 30 the button heads. There is also a ratchet mechanism 96' that is operated by a rod 97, which is connected to the main operating lever 10. The specific manner in which this hopper is rotated with each movement of the 35 main oscillating lever 10 is of no importance to the understanding of the present invention and, therefore, is not described.

Now, there is a second oscillating lever 30, as may be seen in Figs. 1 and 2, and it is 40 the movement of the main lever 10 that actuates this irregularly-shaped oscillating lever 30. The latter lever is provided with a slot 31 in which travels the pin 32, which pin 32 is fastened to the oscillating lever 10.

45 At the lower end of the second oscillating lever 30 is the yoke 28 connected to the pitman 26, which pitman, in turn, is fastened to the bell crank or tucker lever 33, which latter is the timing element for a number of 50 the parts of the machine.

The above pitman, yoke, and connections are similar to the construction shown in the patent to White, No. 1,567,882 above referred to.

55 It is the movement of the bell crank or tucker lever 33 which operates the tucker slide 40 to advance the tacks or button fasteners onto the block 16, as the tucker lever 33 is slotted at its outer end, as at 33', to engage the downwardly extending pin 34, which is a part of the tucker slide 40.

As heretofore mentioned, a detailed description of the tucker slide and the manner in which it is synchronized with the feeding 65 of the buttons is not thought necessary and

can be seen in detail in the patent granted to Franklin R. White on December 29, 1925, No. 1,567,882.

70 There will now follow a short description of the means for holding the buttons which are acted on by the movement of the main plunger or die.

75 Referring again, therefore, for the moment to Fig. 1, there is shown a button chute 35, which leads from the magazine 96 to beneath the plunger or die 6. There will also be seen the arm 90 which is pivoted, as at 91, the forward portion 92 of the arm extending in an angular relation and having the jaws 93 mounted thereon. These are 80 not the jaws, however, that form the gist of the present invention and should not be confused with them. In a like manner, a supplemental pair of jaws 94 is shown in connection with the jaws 93 for preventing the button from rebounding from the jaws 93 and neither should these jaws be confused with the jaws that form the gist of the invention.

85 It may be mentioned in a general way 90 that when the main oscillating lever 10 is raised, it not only causes the plunger or die 6 to push the arm 92 with its button and jaws downwardly, but it will also cause the oscillating lever 30 to move and, in turn, through the yoke and pitman move the tucker lever 33 which, in turn, will force the tucker slide rearwardly behind the tack escapement (not shown), so that when the oscillating lever 10 is again lowered, the tucker 95 slide on its return movement will force the tack or button fastener out onto the anvil block 16 to be clutched by the jaws 18. The operation of the lever 30 also rotates the magazine 96 and liberates a button and performs other operations that need not be 10 mentioned at this time.

Now, understanding the general operation of the machine, reference will be made to the manner in which the tack holding jaws 11 are formed and operated, and the cam mechanism synchronized with the stroke of the plunger.

It will be understood that where the word 11 "tack" is used, it is used in its broadest sense to cover a tack or other form of button fastening member.

First, referring to Fig. 5, it will be seen 12 that the tucker lever 33 has the cam 36 thereon, which cam has a hardened steel face 37 pinned thereto.

This tucker lever 33 is substantially in the form of a triangular plate and has its apex slotted to encircle the pin 34 for operating the tucker slide.

As also heretofore mentioned, to this plate or tucker lever 33 is connected the pitman 26, so that a movement of the oscillating lever 30 may actuate this tucker lever. There is also a rod 99, a fragmentary por- 13

tion of which is shown in Figs. 3 and 4, that extends up to the hopper which holds the tacks for imparting a ratchet movement to the hopper, so that the tacks may be 5 liberated to the tack chute.

However, the part of the tucker lever which is of most interest is the cam 36 formed near the rear end thereof, as may be seen in Figs. 3 and 4, because as this plate 10 or tucker lever is revolved from the position shown in Fig. 3 to that shown in Fig. 4, it will, besides operating the tucker slide, cause a small lever 41 to be operated, which lever 41 places the jaw carrier under pressure to thus lower the carrier and jaws, when the jaws are unlocked from the anvil, as will be shortly described.

As may be seen, the tucker lever 33 is partly cut-out on its under surface, as at 38, to receive the handle 39, so that this tucker lever 33 may be hand-operated in case a tack becomes jammed in the tucker slide. This feature is shown and described in full in patent, No. 1,567,882, above referred to.

Referring to Figs. 10 and 15 for the moment, there is shown the cam lever 41 which is formed of the two parts 42 and 43, the parts being pivotally joined about the pin 44. The heel 45 is slightly rounded to provide as little friction as possible in riding up the hardened surface 37 of the cam 36 formed on the tucker lever 33. The nose or forward end 46 of the cam lever 41 projects over and normally rests on the vertical movable jaw carrier 17', which is in the form of a sleeve which travels on the anvil post 17, as may be clearly seen in Figs. 11 and 12. This carrier will be described shortly 45 in detail.

The lever part 43 has the little upwardly extending lug 47 near its forward end, while a projection or lug 48 is on the rear portion 42, so that a small compressible spring 49 may be mounted on a pin 50, which extends between the two lugs. The pin 50 and the spring are assembled and assisting their assembly is the small nut 51, which is screwed up to the shoulder or lug, after 50 which a check nut is placed in back of the same.

The pin will, of course, be provided with the little integral nose 52, while a collar 53 may be seen at the rear end of the spring. The nose will fit within a slight depression (see Fig. 10) in the forward lug 47 of the lever. The pin, with the spring 50 under heavy compression, is fitted between the two 60 parts, and it will be readily understood that a tightening of the nut will increase the compression of the spring but loosen the compression between the two parts of the lever, while a forward movement of the pin 50 will tend to force the two parts of the lever

slightly apart, there still being plenty of compression in the spring.

There is, however, very little play between the two parts of the lever, as the shoulders of the tongue and groove connection, shown 70 at 44, (Figs. 10 and 16) are so cut that the parts will abut with but a slight relative movement of one part to the other. The purpose in having these two parts of the lever slightly adjustable, however, is so that when this cam-operated lever forces down the jaw carrier and jaws, the lever will not break before the jaws are unlocked, and also any sudden shock may be dissipated in the 75 spring rather than possibly snap the lever. 80

Still referring to Fig. 10, there is seen a coil spring 54 under the carrier 17' to normally hold the carrier in its upper position, this carrier fitting over the anvil post 17, which latter fits within the bore of the forward end of the table. It will be understood 85 that when the tucker lever 33 is operated from the position shown in Fig. 3 to the position shown in Fig. 4, through the movement of the oscillating levers 10 and 30, the heel 45 of the lever 41 rides up the cam 37. The pressure of the lever 41 on the carrier 17' will now be far greater than the upward pressure exerted by the light spring 54. Thus, when the jaws are spread apart, 90 that is, unlocked from the anvil, as will be shortly described, the carrier will be forced rapidly downward.

In Patent No. 1,497,819 heretofore referred to, a certain form of tack holding 100 jaws was illustrated and referred to, which jaws were fitted on a carrier somewhat similar to the present carrier, but the jaws had to be moved out of the way by the operator moving the cloth. In the present application, however, the jaws are forced apart and unlocked by the button being driven on the tack and are then forced downwardly by the cam and lever action, remaining in this lowered position for a certain interval of 105 time, to wit, about one-third of the upward movement of the plunger, as will also be shortly described in detail.

Referring now more specifically to the anvil post and the jaws, it will be seen that this post 17 has the anvil or head 16 at the top thereof, the top surface of this head being shaped slightly, as at 55, to accommodate the curvature of a tack or fastener head. It will also be noticed that on the opposite sides of this anvil and spaced slightly from its top surface are the two locking grooves 56. This anvil, of course, is directly beneath the main plunger 6.

Slidably mounted about the post 17 is the 115 carrier 17' which has the small jaws 18 pivotally mounted therein. It might be mentioned that forming a part of this carrier is the front upright 57 and the rear upright 57', and to these uprights are pivoted the 120 130

jaws 18 by the little pivot pins 58, these jaws operating between the two uprights, as may be seen in the several views.

These little jaws 18 are also each provided with a little notch 59 in the front faces of their stems, so that the respective ends of a spring or resilient member 60 may fit within these notches 59 to normally hold the jaws in the compressed position. There is also shown a spring holder 61, which is attached to the upright 57 mounted on the carrier 17', which holds this compressible member in position, as may be seen in Figs. 1 and 2. This little spring carrier is also illustrated in detail in Patent, No. 1,497,819.

Referring again for the moment to the jaws 18, it will be seen that on the inner surfaces of their stems they are each provided with a little nib 62 which is designed to normally rest within the grooves 56 that are formed within the anvil 16. They are shown in their normal locked position in detail in Fig. 6.

The jaws at their respective noses are slightly indented or nicked (see Figs. 3 and 4), as at 63, so that when a tack 64 is forced into the jaws by the tucker slide 40 and the jaws are closed the recesses 63 will encircle the prong of the tack to hold it rigidly in position.

As may be clearly seen in Figs. 6 and 7, the nose 46 of the cam-operated lever 41 rests on the upper surface of the jaw carrier 17' that carries the jaws 18 just referred to, to force the carrier and the jaws downwardly when the button is jammed down on the tack.

It will be understood that when the carrier 17' is in its normal position, the jaws 18 will be in the position shown in Figs. 1 and 3, the jaws will tightly grip the tack 64, which is resting on the anvil 16, which tack has been forced by the tucker slide out onto the anvil, and the jaws will be locked with relation to the anvil.

Referring to Fig. 14 for the moment, wherein the carrier is shown in perspective, it will be noticed that in the left upright 57 there is formed the keyway or slot 65, which is adapted to slidably fit about the front 66 of the anvil head 16 to thus prevent the carrier 17' from revolving or moving out of its proper vertical alignment. Also, the rear upright 57' of the carrier is designed to fit within a groove of the tucker mechanism, as may be seen in Fig. 12 to thus further steady the carrier in its vertical movement.

In Figs. 11 to 15 inclusive, the anvil post and the anvil, as well as the carrier, are shown in enlarged detail with the jaws removed, so that the detailed construction of this mechanism may be more clearly understood.

The lower portion of the carrier 17' is circular and then tapers inwardly and down-

wardly, as at 67, as also may be seen in the several views, while the light spring 54, as will be understood from the several views, encircles the post 17 and extends up beyond the tapered portion 67 and rests beneath 70 the forward and rear uprights of the carrier.

Operation

Supposing there is a button within the jaws 93 on the button receiver and directly beneath the plunger 6 and presume there is a tack 64 resting on the anvil 16. The cloth to which the button is to be attached will be placed directly over the jaws and a clutch (not shown) operated which will, through a rod (not shown) move the main oscillating lever 10 upwardly. This will start the plunger in its downward course and will also move the oscillating lever 30, which lever, it will be remembered, is connected to the bell crank or tucker lever 33. After the plunger 6 has descended about one-fourth of its stroke, the heel 45 on the jaw carrier operating lever 41 will contact with the hardened face 37 of the cam 36 and, of course, the nose 46 of the lever 41 will bear downwardly on the carrier 17'. The heel of the lever will ride up the cam to its top surface, and the plunger 6 will have passed downwardly and forced the button B down on the upper surface of the jaws 18 and also will have forced the button head on the tack 64. Furthermore, the tucker slide is driven rearwardly, so that it will drive another tack forwardly when the tucker slide again advances.

As the button head presses on the beveled upper surface of the jaws 18, the cloth and the button head will force the jaws apart until the little nibs or projections 62 are forced from their recesses 56 within the anvil, and as the nose of the cam lever 41 is bearing with great force on the carrier, the moment the jaws are unlocked from the anvil the carrier will be rapidly forced downwardly from the position shown in Fig. 6 to the position shown in Fig. 7. It will be remembered now that the lever 41 has ridden up the cam 36 and will be at rest on the top surface thereof.

Now, the tack will have been driven through the cloth and up into the button head and the button properly attached to the cloth. The main oscillating lever 10 will now be in the position shown in Fig. 2.

Looking for the moment at Fig. 2, it will be seen that the main oscillating lever 10 will have its pin connection with the oscillating lever 30 travel down the slot 31 from the full line position to its dotted line position before the oscillating lever 30 starts to move, as the main lever is pivoted, as at 11, and the radii from the dotted line position to the full line position of the pin 32 is the same.

Thus, the main oscillating lever 10 and the plunger 6 may rise way above the jaws 18 and, in fact, up to substantially the level of the button carrier jaws 93, even before the bell crank or tucker lever 33 comes into motion which, of course, is brought about by the movement of the oscillating lever 30. Therefore, we have the button attached to the cloth and the plunger moved considerably above the jaws 18, so that there is plenty of time during this upward movement of the plunger for the operator to remove the cloth and the attached button. Now, after the oscillating lever 10 has lowered to the dotted line position of Fig. 2 and continues in its descent, it will start to move the lever 30 and this, in turn, will tend to swing the tucker lever 33 again toward its normal position, the tucker slide advancing a new tack. The little heel of the cam-operated lever 41 will start down the face of the cam and the pressure thus being relieved from the carrier by this operating lever will allow the spring 54 under the carrier to again raise the carrier and its jaws 18. The jaws will now ride up the sides of the anvil, as shown in Figs. 8 and 9, and as the jaws rise they will naturally push on the under surface of the cloth. If the operator has failed to move the same and as the jaws continue to rise, due now to the pressure of the spring 54 under the carrier, and there is no pressure being exerted on the cam lever, they (the jaws) will assume the position shown in Fig. 9. Also, due to their spring action, the jaws will snap together when they have reached their uppermost position and the nibs 62 will again engage the slots and lock within the same, and the jaws will hold another tack tightly on the anvil.

As shown in Fig. 9, there is no danger of these beveled jaws grasping the head of the tack or fastener just driven through the cloth, as the cloth, being pushed upwardly by the jaws, will cause the tack head to be lifted slightly above the noses of the jaws.

The jaws are now closed and, as mentioned, the lever 41 descends to its final position, the escapement for the tacks has operated, and the tucker slide will have forced a tack out onto the anvil 16. The slide will extend between the two jaws to push the tack into the little recesses formed in the tops of the jaws, where it will be tightly clutched until the next button is driven down thereon. In the meantime, of course, another button head will have been liberated down the button chute, so that the machine is ready for a successive operation.

Thus, it will be seen that by providing a cam face on the tucker lever 33 at the desired location thereon, and by synchronizing the several parts, as heretofore explained, the plunger may descend about one-fourth of its

stroke before the cam-operated lever begins to ride up the cam surface to exert a downward pressure on the jaw carrier with its jaws, and likewise the plunger may return through a part of its upward movement before the cam begins to ride from beneath the cam-operated lever. Thus, the jaws will remain in their open position for about one-third of the upward stroke of the plunger before the jaws again snap shut, which will give the operator plenty of time between strokes to move the cloth with the attached button.

Furthermore, should the operator fail to remove the cloth, the little jaws in their upward movement will bear against the cloth, so that there is no danger of the jaws when they do snap shut to again grasp the head of the fastener of the attached button.

It will be noticed that the little cam-operated lever is away from the cloth so as not to hinder the operator and provides plenty of time for the operator to remove the cloth, nor can the attached button jam should the operator be careless.

I have shown a coil spring in the operating lever cam, but I do not wish to be limited to the exact form of spring here illustrated, nor to the exact construction of the lever 41, as other similar levers and springs might be utilized without departing from the spirit and scope of the invention.

The machine, as illustrated and described above, has given very efficient service and makes it possible for less-skilled operators to use the machine than might otherwise be necessary.

Having thus described my invention, what I claim as new and desire to secure by Letters Patent is:—

1. A button attaching machine including an undercut anvil post for supporting a button fastening member, a jaw carrier slidably mounted on said post, jaws secured to said carrier, a spring for normally holding the jaws under compression, and the jaws and the anvil post interlocking to normally hold the button fastening member on said anvil post.

2. A button attaching machine including an anvil for supporting a button fastening member, said anvil being undercut just beneath its top surface, jaws extending on the opposite sides of the anvil to hold said button fastening member, the anvil and jaws provided with interlocking means to hold the jaws normally interlocked about said undercut anvil.

3. A button attaching machine including an anvil for supporting a button fastener, a jaw carrier vertically movable on said anvil, spreadable jaws mounted in said carrier and having parts to normally interlock with said anvil, the jaws adapted to grip the button fastener when on said anvil, and means al-

- ways bearing on the jaw carrier for forcing said jaw carrier downwardly when said jaws are spread and thus unlocked from said anvil.
- 5 4. A button fastening machine including a plunger and means for moving the same, an anvil, a jaw carrier vertically movable on said anvil, spreadable jaws mounted in said carrier, the jaws and the anvil having parts normally interlocked, said jaws being adapted to grip a fastener when on said anvil, the plunger being adapted to force a button on said fastener and also spread the jaws, and means for forcing said jaw carrier downwardly when the said jaws are thus spread.
- 10 5. A button fastening machine including a plunger, means for moving the same, an anvil, a jaw carrier vertically movable on said anvil, spreadable jaws mounted in said carrier, the jaws and the anvil having parts interlocked, said jaws being adapted to grip a fastener on said anvil when the plunger is in a raised position, said plunger being adapted to force a button on said fastener and in doing so to spread said jaws, and means for forcing said jaw carrier downwardly when the said jaws are thus spread and to cause the jaws to remain in their lower position through an initial part of the upstroke of said plunger.
- 15 6. A button attaching machine including a plunger and means for moving the same, an anvil, fastener gripping means located about said anvil and normally locked therewith, said gripping means being unlocked when the plunger indirectly acts on the gripping means, means synchronized with the plunger for forcing the gripping means downwardly, and said means also holding the gripping means in its lowered position through a part of the return stroke of the plunger.
- 20 7. In a button attaching machine, a fastener holding means including an anvil having indentations cut therein to form substantially a T-head, a jaw carrier vertically movable on said anvil, and pivotal jaws mounted thereon and having parts normally locking within said indentations.
- 25 8. A button attaching machine including a tack gripping means, said means including a slideable jaw carrier, an anvil, jaws pivoted in said carrier, means for holding the jaws together, means for holding the jaw carrier in its uppermost position, means for locking the jaws to the anvil, and means always bearing against the jaw carrier for driving the jaw carrier downwardly when said jaws are unlocked from said anvil.
- 30 9. A button attaching machine including a tack supporting anvil, a jaw carrier mounted for vertical movement on said anvil, jaws in said carrier, means for locking the jaws with relation to the anvil, means for holding the jaws in their locked position, means for forcing the carrier and jaws downwardly when the jaws are unlocked, and means to prevent the rotation of said jaw carrier about said anvil.
- 35 10. A button attaching machine including a jaw carrier, an anvil, said jaw carrier mounted for vertical movement on said anvil, spreadable jaws on the carrier, said jaws normally interlocked with said anvil and unlocked from said anvil when in their spread position, and cam means for forcing said jaw carrier downwardly when said jaws are unlocked from said anvil.
- 40 11. A button attaching machine including a plunger, tack gripping jaws beneath said plunger, an anvil beneath said plunger, said tack gripping jaws slidably movable on said anvil, said plunger adapted to indirectly spread said jaws, and cam means for forcing said jaws downwardly when said jaws are spread, said cam means being synchronized in motion with the plunger so that the jaws will remain in their lowered position for substantially one-third of the upstroke of the plunger.
- 45 12. A button attaching machine including an anvil for supporting a button fastener, a plunger located above the same for driving a button head on the fastener, fastener gripping means including jaws associated with the anvil and normally interlocking with said anvil, and means for lowering said jaws, said means being synchronized with the stroke of the plunger whereby the jaws remain closed during the greater part of the downstroke of the plunger and remain open during substantially one-third of the initial upstroke of the plunger.
- 50 13. A button fastener holding means including a jaw carrier, pivotally mounted jaws in said carrier, said jaws tapering toward their respective noses to form a dished surface, the said noses provided with recesses adapted to grip a button fastener, and means on the stems of the jaws adapted to interlock with an anvil.
- 55 14. A button fastener holding means including a jaw carrier, pivotal jaws mounted on said carrier, the said jaws tapering from their respective noses to form a V-shaped upper surface, said noses provided with recesses adapted to grip a button fastener, and means on the stems of the jaws adapted to interlock with an anvil when the respective noses of the jaws are adjacent one another.
- 60 15. A button fastener gripping means including a rectangular jaw carrier adapted for vertical movement, pivotal jaws mounted in said carrier, and spring means extending from the carrier to the jaws for normally holding the jaws together, a portion of the jaw carrier being adapted to slide within a frame to prevent the jaw carrier from moving out of vertical alignment.
- 65 16. A button fastener gripping means in-

cluding an anvil, a rectangular jaw carrier adapted to move vertically upon said anvil, jaws on said carrier, spring means extending from the carrier to the jaws for normally holding the jaws together, and a portion of the jaw carrier being adapted to slide within a frame and another portion of the jaw carrier gibbed and keyed to the anvil to prevent the jaw carrier from moving out of vertical alignment.

17. A button fastener gripping means including a rectangular jaw carrier, an anvil, the said jaw carrier being capable of movement up and down upon said anvil, the anvil and jaw carrier having interlocking faces to prevent misalignment of the jaw carrier with the anvil, pivotal jaws mounted in said carrier, spring means extending from the carrier to the jaws for normally holding the jaws together, the said jaws and anvil formed to interlock when the jaws are in their closed position, and spring means about said anvil for holding the jaw carrier in its upper position and permitting the jaws to interlock with said anvil.

18. A button attaching machine including a tucker mechanism, a tucker lever for operating said mechanism, an anvil, a jaw carrier with jaws movable along said anvil, and means on said tucker lever for cooperating with means resting against said jaw carrier for forcing said jaw carrier downwardly when said tucker lever is operated.

19. A button attaching machine including a tucker mechanism, a tucker lever for operating said mechanism, an anvil, a jaw carrier provided with movable jaws, the said carrier movable up and down upon said anvil, a cam on said tucker lever, and a lever cooperating with said cam and said jaw carrier for forcing said jaw carrier downwardly when said tucker lever is operated.

20. A button attaching machine including a tucker mechanism, a tucker lever for operating said mechanism, means for operating the tucker lever, an anvil, a jaw carrier provided with movable jaws adapted to grip a fastener when on said anvil, the said carrier being vertically movable on said anvil, a cam on said tucker lever, and means extending between the cam and the jaw carrier for forcing said carrier downwardly when said tucker lever is operated.

21. A button attaching machine including a tucker mechanism, a tucker lever for operating said mechanism, a plunger synchronized in motion with the tucker lever, an anvil, a jaw carrier provided with movable jaws adapted to grip a fastener when on said anvil, the carrier being vertically movable on said anvil, a cam on said tucker lever, and means extending between the cam and the jaw carrier for forcing said carrier downwardly when said plunger and tucker lever are operated.

22. A button attaching machine including a tucker mechanism, a tucker lever for operating said mechanism, means for operating the tucker lever, an anvil, a jaw carrier provided with movable jaws adapted to grip a fastener when on said anvil and the jaws being normally locked with said anvil, a plunger for forcing a button head on said fastener, a cam on said tucker lever, and means extending between the cam and the jaw carrier for forcing said carrier downwardly when the jaws are unlocked by said plunger and the tucker lever is operated.

23. A button attaching machine including an anvil, a jaw carrier provided with pivotal jaws movable on said anvil and the jaws being normally locked with said anvil, a tucker mechanism for advancing a tack onto said anvil, a tucker lever for operating said tucker mechanism, and means cooperating with the tucker lever and the jaw carrier for forcing said jaw carrier downwardly when said tucker lever is operated.

24. A button attaching machine including an anvil to support a fastener, a jaw carrier provided with spreadable jaws movable on said anvil, the jaws adapted to grasp a fastener when on said anvil, said jaws being normally locked with said anvil, a tucker mechanism for advancing a fastener to said anvil, a tucker lever for operating said tucker mechanism, means for indirectly spreading said jaws to thus unlock the same, and means cooperating with the tucker lever for forcing said jaw carrier downwardly when said tucker lever is operated.

25. A button attaching machine including a plunger, an anvil and spreadable retractile jaws on said anvil, a tucker slide, a tucker lever, the plunger being adapted to indirectly spread the said jaws, and means independent of the plunger for retracting said jaws as the tucker lever moves said tucker slide rearwardly.

26. A button attaching machine including a fastener gripping mechanism, a tucker mechanism for advancing a fastener to said gripping mechanism, a tucker lever for operating said tucker mechanism, and cam means cooperating with said tucker lever whereby said jaws are retracted when said tucker slide is moved rearwardly.

27. A button attaching machine including a tucker lever, a cam face on said tucker lever, an anvil, a retractile jaw carrier and jaws movable on said anvil for holding a fastener, and a lever having its heel resting on said tucker lever and its nose resting on said jaw carrier whereby said jaw carrier is lowered when said tucker lever is operated.

28. The combination of a tucker lever provided with a cam surface thereon, a two-piece lever, a compressible spring between the two parts of said lever, and a retractile jaw carrier, the nose of said last-mentioned

lever resting on said jaw carrier whereby an operation of the tucker lever will force said jaw carrier downwardly.

29. The combination of an anvil, a jaw carrier movable on said anvil, pivotal spreadable jaws for holding a fastener on said carrier, a two-piece compressible lever pivotally mounted by the side of said jaw carrier and having its nose extending onto said jaw carrier, and a tucker lever provided with a cam face for operating the two-piece lever to thereby force said jaw carrier downwardly when said tucker lever is operated.

30. An anvil, a jaw carrier on said anvil, pivotal jaws in said carrier, means on the jaws and carrier for normally locking the jaw carrier against movement when in its upper position, a two-piece compressible lever provided with spring means therein, and a tucker lever cooperating with said two-piece lever, said tucker lever being provided with a cam whereby a movement of said tucker lever will move said jaw carrier downwardly when the jaws are unlocked from said anvil.

31. An anvil, a jaw carrier on said anvil, pivotal jaws in said carrier, means on the jaws and carrier for normally locking the jaw carrier against movement when in its upper position, a two-piece compressible lever provided with spring means therein, a tucker lever cooperating with said two-piece lever, said tucker lever being provided with a cam whereby a movement of said tucker lever will move said jaw carrier downwardly when the jaws are unlocked from said anvil, and a spring for normally holding said jaw carrier in its uppermost position.

40 In testimony whereof I affix my signature.
FREDERICK H. PETERSON.
